United States Patent Office.

FREDERIC CHASE, OF PHILADELPHIA, PENNSYLVANIA.

Letters Patent No. 82,491, dated September 29, 1868.

IMPROVED ZINCKING OR TINNING-BATH.

The Schedule referred to in these Letters Patent and making part of the same.

TO ALL WHOM IT MAY CONCERN:

Be it known that I, FREDERIC CHASE, of the city of Philadelphia, in the State of Pennsylvania, have invented a new and useful Zincking and Tinning-Bath; and I do hereby declare that the following is a full, clear, and exact description of the same, reference being had to the accompanying drawings, making a part of this specification, in which—

Figure 1 is a plan view of the said vessel,

Figure 2 a transverse section of the same, and

Figure 3 an enlarged horizontal section of part of the side of the same—

Like letters and numbers of reference indicating the same parts when in the different figures.

Baths or vessels used for coating large plates, tubes, &c., of iron with zinc or tin, have heretofore been made of thick plate-iron, and cost from five to eight hundred dollars for one of the common size. The action of the contained melted metal upon the iron vessel produces an alloy or dross which is not only objectionable in the coating-métal, but the vessel itself becomes, in consequence, unfit for use in the course of eighteen months or two years. In order to obviate these objectionable results, a "lining" of other metals has lately been applied to the inner side of the iron vessel, but this application still further increases the cost of iron vessels, and is, besides, of doubtful efficiency.

The object of my invention is to produce a bath or melting-vessel for zincking or tinning large plates, tubes, &c., of iron, the original cost of which will be much less than the iron vessels of the same size, will last much longer in use, and cannot, owing to the materials of which it is made, alloy with the contained melted metal or produce dross of any kind.

My invention consists, first, of a bath or vessel for zincking or tinning large plates, &c., of iron, made bodily of fire-clay, or its equivalent earthy substance, and, second, in the mode of constructing the said fire-clay bath or vessel, substantially as hereinafter described and specified.

To enable others to understand and make my said zincking or tinning-vessels, I will proceed to describe their construction.

Referring to the drawings, A is the bottom of the bath or vessel, and B B its upright sides.

I make the sides, B, and the bottom, A, of fire-clay, and unite them together in the following manner:

I construct the sides B by moulding the fire-clay into the form of staves 1', each about four inches in thickness and ten or twelve inches in width, more or less, and of proper length for the purpose, say four feet, tongued and grooved correspondingly at their edges, and the tongue 2, as well as the bottom, 3, of each groove, with a supplementary groove, 4, made along in their mid-widths from end to end of the stave, substantially as represented in fig. 3, and then dry them slowly, and finally harden them by heat in a kiln in the usual manner practised in making fire-bricks and slabs. I then "set" the said staves 1' "up" together, with their respective tongues 2 and grooves 3 interlocking, so as to produce the required flat, oval, or other required form, of the sides of the vessel, substantially as represented in fig. 1, upon the intended supporting-base or platform provided for it over or within the melting-furnace usually adopted for supporting and heating the iron vessels, (see the faint lines in fig. 2,) and bind them tightly and firmly together at their edges by means of one or more bands or hoops of plate-iron, 5, having its ends coupled together by a tightening-screw, 6, so that the said band or bands can be firmly tightened around the outer side of the vessel, (see figs. 1 and 2.) I now adjust the position of the vessel on the platform, and then form the bottom A, out of the raw material of which the sides B were made, by packing it in a plastic state upon the platform or supporting-base, but within and around the outside edge of the vessel, so as to produce the said bottom, A, of sufficient depth or thickness, say about five inches, more or less; and, finally, I then mix up a sufficiency of the raw, plastic fire-clay and water into a semi-fluid, and with it fill thoroughly all the supplementary grooves, 4, in the vessel A, and let the whole stand undisturbed until dry, after which the furnace may be ignited, and the filling in the grooves 4 and the bottom A, will soon become sufficiently baked and hard to allow of the reception of the melted metal, and a continuous operation of the process of zincking or tinning in the usual manner.

It will be seen that as the vessel or bath A. B is made entirely or bodily of fire-clay, or an equivalent earth, with the exception only of the outside band 5, the objectionable alloy or dross which occurs in the iron vessels heretofore used cannot arise, and that the cost of my said vessels will be much cheaper in their original construction than those of thick plate-iron, whether the latter be "lined" or not, and that from the fact that the material of which the vessel is made does not contain any metal, a waste by alloying cannot occur, and therefore the vessel A. B will last much longer.

The cost of material and construction of one of my said baths or vessels, of the size of the large iron vessels in general use, and which cost from five hundred to eight hundred dollars, will not be more than from one hundred to one hundred and fifty dollars, and will last five or six years in use.

I am aware that a patent was granted to Frederick A. Kraft for "lining the cast or wrought-iron vessels with a substance which will not be affected by or form an alloy with the zinc, and which will not so readily form an alloy with the heated iron." I therefore do not desire to claim lining a zincking or tinning-vessel or bath with fire-clay, or any other material suggested in said patent; but having thus fully described my invention,

What I claim as new, and desire to secure by Letters Patent, is—

A zincking or tinning-bath or vessel, constructed bodily of fire-clay, or its equivalent earthy substance, substantially as described.

I also claim constructing a zincking or tinning-bath of fire-clay, or its equivalent, substantially in the manner set forth and described.

FREDERIC CHASE.
